(57) **CLAIM**

The ornamental design for an insertion aid for voice prosthesis, as shown and described.

DESCRIPTION

FIG. 1 is a top plan view of the insertion aid for voice prosthesis showing a first embodiment of my new design; FIG. 2 is a perspective view of the top, front and side thereof;

FIG. 3 is a side elevational view thereof, the other side is a mirror image;

FIG. 4 is a bottom plan view thereof;

FIG. 5 is an enlarged front elevational view thereof;

FIG. 6 is a top plan view of the insertion aid for voice prosthesis showing a second embodiment of my new design; FIG. 7 is a perspective view of the top, front and side thereof;

FIG. 8 is a side elevational view thereof, the other side is a mirror image;

FIG. 9 is a bottom plan view thereof;

FIG. 10 is an enlarged front elevational view thereof;

FIG. 11 is a top plan view of the insertion aid for voice prosthesis showing a third embodiment of my new design; FIG. 12 is a perspective view of the top, front and side thereof;

FIG. 13 is a side elevational view thereof, the other side is a mirror image;

FIG. 14 is a bottom plan view thereof;

FIG. 15 is an enlarged front elevational view thereof;

FIG. 16 is a top plan view of the insertion aid for voice prosthesis showing a fourth embodiment of my new design; FIG. 17 is a perspective view of the top, front and side thereof;

FIG. 18 is a side elevational view thereof, the other side is a mirror image;

FIG. 19 is a bottom plan view thereof; and,

FIG. 20 is an enlarged front elevational view thereof.
